(57) **CLAIM**

The ornamental design for a distribution cart, as shown and described.

DESCRIPTION

FIG. 1 is a front perspective view of a distribution cart according to the present design;

FIG. 2 is a rear perspective view of the distribution cart of FIG. 1;

FIG. 3 is a front view of the distribution cart of FIG. 1;

FIG. 4 is a rear view of the distribution cart of FIG. 1;

FIG. 5 is a right side view of the distribution cart of FIG. 1;

FIG. 6 is a left side view of the distribution cart of FIG. 1;

FIG. 7 is a top view of the distribution cart of FIG. 1;

FIG. 8 is a bottom view of the distribution cart of FIG. 1; and,

FIG. 9 is a right side perspective view of the distribution cart of FIG. 1 when used to transport a plurality of totes.

The broken lines illustrating the wheels, casters and hitch feature are included to show portions of the distribution cart. The broken lines illustrating totes in FIG. 9 are included to show environment. All broken lines form no part of the claimed design.

1 Claim, 8 Drawing Sheets
